(57) **CLAIM**

The ornamental design for eyeglass cleaner, as shown and described.

DESCRIPTION

FIG. 1 is a front closed perspective view of a eyeglass cleaner showing my new design;

FIG. 2 is a top closed view thereof;

FIG. 3 is a front closed view thereof;

FIG. 4 is a rear closed view thereof;

FIG. 5 is a right closed side view thereof; The left closed side view is a mirror image and not shown.

FIG. 6 is a front open perspective view thereof;

FIG. 7 is a top open view thereof;

FIG. 8 is a front open view thereof;

FIG. 9 is a rear open view thereof; and,

FIG. 10 is a right open side view thereof; The left open side view is a mirror image and not shown.

Interior structure shown in broken lines for illustrative purposes only and forms no part of the design.

The bottom is flat and unornamented and forms no part of the design.
